APPARATUS FOR THE PRODUCTION OF COMBUSTIBLE GASES FROM SOLID CARBONACEOUS MATERIALS

Thomas E. Ban, Cleveland Heights, Ohio, assignor, by mesne assignments, to McDowell-Wellman Engineering Company

Filed Jan. 2, 1962, Ser. No. 163,502
2 Claims. (Cl. 48—63)

This invention relates as indicated to an improved apparatus for the production of combustible gases from solid carbonaceous materials, such as coal, and more particularly to a continuous system for the production of producer gas or coal gas from such solid carbonaceous fuels.

The production of producer gas or "water gas," coal gas, and coke for metallurgical purposes is an art which has been practiced for many years. It has now been found that greatly increased efficiency can be achieved in the production of such products by causing the interaction of gases and solids by supporting a bed of solids on a continuously moving conveyor including a plurality of pallets and grates, and directing gases through the voids of the solid particles. The following subject matter relates to methods and apparatus for gasifying coal and carbonizing coal or other such solid carbonaceous fuels on such an apparatus, and with a special reference to the well known "Dwight-Lloyd" machine. Gasification of such solid carbonaceous materials as coal as described herein refers to the conversion of the combustible matter to a useful gas. Carbonization of coal or other such solid carbonaceous material as described herein refers to the removal and collection of the volatile matter while converting the residual solids into a pyrolytic char, or coke. This invention will be illustrated with primary reference to the use of coal as the fuel burden, but it is to be understood that the apparatus and processes of the present invention may be applied to synthetic compositions similar to coal such as briquettes comprised of carbon and tar residues, or green (unhardened) pellets composed of ground coal and water.

It is the principal object of the present invention, therefore, to provide a system for the conducting of solid-gas reactions wherein the solid is a solid carbonaceous fuel material.

Other objects of the invention will appear as the description proceeds.

This invention may be better understood by reference to the annexed drawings which are to be understood as being illustrative of a preferred embodiment of the present invention without limiting the invention to the precise scope thereof, and wherein:

FIG. 1 is a diagrammatic and schematic illustration of one form of apparatus for forming producer gas from coal.

FIG. 2 is a diagrammatic and schematic illustration of one form of apparatus useful in the production of coal gas and coke in accordance with the present invention.

Briefly stated, the present invention is in the provision of a system for forming a gas including carbon monoxide, hydrogen and methane from a solid carbonaceous fuel. Ignition means are provided including a plurality of pallets mounted on an elongated horizontally disposed endless conveyor, which pallets have a plurality of spaced grate bars defining the bottom thereof and through which gases may be passed. These pellets are adapted to contain a fuel evenly distributed thereon to form what is termed a fuel burden. The fuel burden is ignited, and means are provided for passing a gas through the fuel burden for the purpose of entraining

and extracting therefrom normally liquid components of the fuel. Depending upon the nature of the gas which is passed through the fuel burden, either producer gas or coal gas will be produced, and the solid by-product of the reaction will be coal ash or coke. The apparatus also includes means for isolating the liquid components from the gas such as a scrubbing tower or condenser, and means for recovering the gas. In a preferred embodiment of the invention, the solid-gas reaction is conducted in a field chamber, and thus the entire endless conveyor-pallet system is enclosed.

Gasification of coal may be represented by two principal reactions as follows:

- 15 (1) $C + O_2 \rightarrow 2CO$ (exothermic)
(2) $C + H_2O \rightarrow CO + H_2$ (endothermic)

The heat of reaction (1) is utilized to sustain the reaction (2) to produce water gas. Air, steam and coal are generally used to make producer gas which results from the simultaneous conduct of both reactions. Water gas results from sequential carrying out of the two reactions above mentioned. Instead of air, oxygen may be used along with the water as the gaseous constituents of the reaction, and coal, coke, charcoal, or other carbon containing materials can be used as the solid phase or solid reactant.

When air and steam are reacted with bituminous coal, a producer gas of the following composition is generally formed:

	Percent
Carbon monoxide	25
Hydrogen	10
Methane	3
Illuminants	1
35 Carbon dioxide	3
Nitrogen	58

Ash, clinker and tar are the usual solid and liquid by-products of the gas producer. An approximate material balance for an apparatus of the type herein contemplated shows the following reactants and products per pound of coal:

	Pounds
Air	4
Water	0.2
Coal	1.0
Products:	
Producer gas	5
Ash	0.2
Tar	0.1

Producer gas is usually used for combustion purposes because it has favorable flame characteristics. It is also used to make synthesis gas and the carbon monoxide and hydrogen is used for making chemicals such as wood alcohol and ammonia, respectively.

A simplified system for making producer gas in a chambered system with Dwight-Lloyd machine of conventional design is illustrated in FIG. 1. The chambered system prevents undesirable, unfiltered drafts from entering the system inadvertently. It is hazardous to allow air into the windboxes containing producer gas because of the possibility of creating an explosive mixture. Thus there is shown in FIG. 1 a sealed chamber enclosing an endless conveyor 10 having a plurality of pallets 11 thereon. The bottoms of the pallets are formed from a plurality of grate bars spaced apart approximately $5\frac{1}{2}''$. This provides sufficient permeability for the gases, and sufficient solid structure to support the fuel burden. Solid carbonaceous fuel, such as coal, is stored in a storage bin 12 fitted with a mechanical feeder 13 which is adapted to regulate the rate of feed co-operatively with

the rate of speed of the conveyor 10. Suitable means such as a hopper 14 are provided to distribute solid carbonaceous fuel on the pallets to a substantial uniform depth as the conveyor 10 is moved past the outlet thereof. The fuel burden or coal bed as shown in FIG. 1 immediately passes under a gas burner 15 where the fuel burden is ignited. Hood 16 which may be a single hood or a plurality of individual hood units substantially covers the conveyor way, and may in desirable instances be sealed through the employment of sliding seals with the pallets to prevent the escape of gases therefrom.

On the underside of the conveyor belt and fuel burden, there is provided a wind box 17 which under the influence of gas pump or fan 18 provides the region of reduced pressure beneath the fuel burden, and hence the downward flow of gas therethrough. Gases from the windbox 17 are conducted by means of conduit 19 to a scrubbing tower 20 of conventional design to effect removal of liquid constituents from the gas. These constituents normally include tar and other liquid hydrocarbon and phenolic fractions. The effluent from this scrubber may be conducted to any suitable storage means, not shown. It is desirable to recycle a small portion of the gas through a side arm 22 by means of a pump 23. This provides a positive pressure within the sealed chamber which prevents leakage of air through joints provided for admission of various components of the apparatus.

By the time the fuel burden reaches the right hand end of the conveyor 10 shown in FIG. 1 it has been reduced to ash. This material is collected in a bin 25 which may be provided with a crushing device 26 to break up clinker to such sizes as may be handled by the exit feeder valve 27. The numerical values given in FIG. 1 show a balance of materials in a specific example.

Referring now more particularly to FIG. 2, similar parts have been given identical numbers. Instead of air mixed with steam or water being introduced to the hood as indicated in FIG. 1, coal gas produced in accordance with the reaction is recycled through conduit 30 to the hood 16. A portion of the gas is bled off to storage through exit pipe 31. Instead of ash and clinker being removed at the end of the conveyor belt as shown in FIG. 1, charcoal or coke is produced and is recovered as a useful product in accordance with FIG. 2. The chambered apparatus of FIG. 2 can be used for carbonizing coal by recycling coal gas through a heated coal bed. By heating one ton of coal in the absence of air, the following products can be formed:

	Pounds
Coke or char	1200
Coal gas	400
Tars and hydrocarbon liquids	400

In accordance with FIG. 2, coal is fed to the pressurized coal system and uniformly layered on the conveyor pallets through the hopper 14, as above indicated. An ignition burner 15 supplies heat to the top layers of coal. As this layer feeds under the hood, recycled coal gas forces the hot zone downward. The heated zone causes the expulsion of gas, hydrocarbon liquids and tars from the coal, and the medium is conducted through a scrubber for removing the liquid fractions. Char or coke is removed from the discharge end of the conveyor and from the chamber by means of a star-gate feeder. Coal gas is a relatively inert medium for transferring heat in decomposing coal. This gas has a general composition as follows:

	Percent
Carbon monoxide	6
Hydrogen	46
Methane	32
Illuminants	4
Carbon dioxide	2
Nitrogen	10

The coal gas recycle system allows a sufficient quantity of gas in the system for transferring heat. The recycled gas may be heated additionally either directly or indirectly if more heat is desired to retain the normally liquid components of the gas in a vaporized state for removal from the sealed chamber system.

There has thus been provided an improved system for solid-gas reactions wherein the solid is a carbonaceous material such as coal and the reactant gas is a moist air or coal gas material. By continuously supplying the coal or other solid carbonaceous material to a horizontally disposed elongated conveyor bed having a plurality of pallets thereon, and in a predetermined quantity, a solid-gas phase reaction may be made to occur with the production of useful products. The coal is ignited, and thereafter the reactant gases introduced for the purpose of removing from the coal volatile components thereof and undergoing reaction therewith for the production of useful products either solid products, liquid products or gaseous products. These reactions are carried out in a sealed chamber, and means are supplied externally of the chamber for separating the products of the reaction to their several useful components.

Other modes of applying the principle of this invention may be employed instead of those specifically set forth above, changes being made as regards the details herein disclosed provided the elements set forth in any of the following claims, or the equivalent of such be employed.

It is, therefore, particularly pointed out and distinctly claimed as the invention:

1. A system for forming and recovering a coal gas rich in hydrogen and methane, and residual carbonaceous solids from granular coal which comprises:
  - (a) a plurality of aligned pallets mounted on an elongated horizontally disposed endless conveyor,
  - (b) means at one extremity of said conveyor for distributing said granular coal to a substantially uniform depth to form a coal burden on said pallets,
  - (c) means, above said coal burden on said pallets and adjacent to said means for distributing, for igniting said fuel burden,
  - (d) separate means including a hood in juxtaposed relation to said aligned pallets for supplying recycle coal gas to said ignited coal burden, and means for supplying air in combination with steam to said ignited fuel burden,
  - (e) sealed chamber means for enclosing said ignition means, said conveyor and said hood and isolating them from the ambient atmosphere,
  - (f) means for passing said coal gas down through said fuel burden on said conveyor, to extract volatiles from said coal and yielding a coal gas rich in hydrogen and methane, and to entrain normally liquid components derived from said coal,
  - (g) means below said conveyor for isolating said liquid components from said coal gas,
  - (h) means connected to said means (g) for recovering said liquid depleted coal gas,
  - (i) means connected to said means (h) for recycling a portion of said liquid depleted coal gas to said hood, and
  - (j) means for recovering residual solids from the other extremity of said conveyor.

2. A system for forming and recovering a gas rich in carbon monoxide, and hydrogen, and residual solids from a solid granular carbonaceous fuel which comprises:

- (a) a plurality of aligned pallets mounted on an elongated horizontally disposed endless conveyor;
- (b) means at one extremity of said conveyor for distributing said granular fuel to substantially uniform depth to form a fuel burden on said pallets;
- (c) means, above said fuel burden on said pallets and adjacent to said means for distributing, for igniting said fuel burden;

- (d) separate means including a hood in juxtaposed relation to said aligned pallets on said conveyor and including means for supplying air in combination with steam to said ignited fuel burden;
- (e) means for passing said steam containing gas down through said fuel burden on said conveyor to effect a water gas reaction therewith and yield a producer gas rich in carbon monoxide and hydrogen, and to entrain normally liquid components derived from said fuel;
- (f) separate means below said conveyor for isolating said liquid components from said producer gas;
- (g) means connected to said separate means (f) for recovering said liquid depleted producer gas;
- (h) means for recovering residual solids from the other extremity of said conveyor; and

5

10

15

- (i) sealed chamber means for enclosing said ignition means, conveyor and hood and isolating them from the ambient atmosphere.
